CUP BEATER

Filed May 21, 1927

UNITED STATES PATENT OFFICE.

LAVERN BORDWELL, OF NEW YORK, N. Y.

CUP BEATER.

Application filed May 21, 1927. Serial No. 193,176.

This invention relates to improvements in cup beaters. The construction, mode of operation and objects of the improvement will be specifically pointed out hereinafter.

5 The primary object of this invention is the making of an eight-blade beater specifically constructed so that the blades have their upper or collateral portion interlaced, as well as their lower portion, so that it is particularly adapted for use for beating the material in a cup or a long narrow receptacle such as a tall glass, jar and the like.

10 In cup and tumbler beaters applicant has found by experiment that the beating result is very much increased by shaping the eight blades so that in operation their upper portions interlace as well as their lower portions, and in such beaters, due to the small space of the container, it is necessary to have the 15 blades close together, and the blades instead of interlacing only at their lower ends, they must interlace throughout their length in order to produce the proper beating effect on the material in the small cup or tumbler container.

20 Although applicant has been for many years the manufacturer of eight-blade beaters, and his employees have for years been working from time to time with the end in view of discovering how to make an eight-blade beater of a narrow type to prevent interference of the eight blades, applicant has only comparatively recently discovered the 25 present improvement which accomplishes the end in view.

30 It has been discovered by applicant that by making the eight blades of the two separate beaters substantially straight from their upper to their lower ends, so that they have 35 a slightly larger lower end than upper end, combined with a U-shaped rod having its sides parallel from end to end, the blades will just miss each other at their lower portion, thus producing a construction which rotates 40 with clearness and interference of the blades is prevented.

45 In order to prevent interference between the blades in a beater of the type above referred to, I find it desirable to construct the 50 blades so that they will hold their shape under the strain to which they are subjected in use, and thus prevent them from interfering. In the present construction the above end is accomplished by forming the blades with a 55 longitudinal corrugation whereby they are strengthened so as to hold their shape.

It is also found advantageous for several reasons to have the indentation of this corrugation on the outer sides of the blades while the indentation projects inwardly. It is 60 found that this prevents spattering or splashing of the material being operated upon, and especially prevents small quantities of the material from spattering out of a cup or tumbler since the corrugation causes it to pour 65 sidewise at the lower ends of the corrugations. The corrugations strengthen the blades of the beater; and the indentation extending inwardly, makes the device easy to be cleaned. It will be observed that by making the corrugations in the upper or collateral portion of the blades extend inward, the 70 indentation is exposed outside as the blades revolve, so that the corrugations are readily cleaned, which would not be true if the indentations were reversed and which would place it always inside where access to it would be extremely difficult.

75 Applicant is aware that several attempts have been previously made to construct a beater adapted for use in a tumbler, cup or similar device, but so far as applicant is aware, none of them have heretofore been successful.

In the accompanying drawings:

80 Figure 1 is an elevation showing a beater comprising my improvements.

Figure 2 is a view taken at right angles to Figure 1.

85 Figure 3 is a longitudinal section taken 90 through the central portion of one of the beater blades showing the said corrugation.

Figure 4 is a horizontal sectional view on the line 4—4 of Figure 3.

90 This invention as has already been stated, relates specifically to certain improvements in the beater blades and in the rod on which these blades are supported. Referring to the accompanying drawings, 1 is a drive wheel to which a suitable handle 2 is attached. This 100 drive wheel is journaled in any suitable manner at 2' upon a handle 3. Usually in constructing my present improvements, the lower end of the handle is formed into a U-shape frame 4, to which the upper ends 5 of the 105 U-shaped rod 6 are attached in any suitable manner. Therefore I do not limit myself in any way to the construction of the drive wheel, the handle or the frame at the lower end of the handle.

110 Turning now to the present improvement, I call attention first to the fact that the U-

shaped rod 6 has its sides made parallel from end to end and that the said frame is very narrow. This is found to be desirable for reasons hereinafter referred to.

5 In the drawings a tumbler 7 is shown in dotted lines and the device shown in place within it.

The beaters 8 each comprise two sets of blades which are so constructed that it is 10 adapted to be operative in a tall narrow receptacle, and at the same time it may also be operated in a cup.

Attention is especially directed to the construction of the beater blades 9 that compose 15 the beaters 8. It will be observed from the drawings that the beater blades 9 extend in substantially a straight line from their upper to their lower ends 10, their lower ends 10 being turned horizontal. The upper ends of 20 these blades have pinions 11 attached thereto which are of a usual construction. It will also be noted and particularly shown in Figure 1, that the beater is formed by making its lower end larger than its upper end, and 25 that the blades 9 composing each beater extend in a substantially straight line from their upper to their lower ends.

From the above and from the said Figure 1, it will be noted that each beater is of an elongated, narrow, truncated cone shape from 30 end to end. Applicant finds that this construction is particularly adapted to fit in a narrow receptacle, and furthermore that the said blades will not interfere from end to end by forming them in the above shape. By this 35 it is meant to convey that the blades have an angle from end to end which just enables them to escape each other, especially at their lower ends, leaving them free to rotate without any pounding action whatever. Applicant believes he is the first one to so 40 construct the beaters that the above results are accomplished.

Furthermore in carrying out the present improvement, the blades are strengthened 45 against lateral displacement, and thus prevented from getting out of shape and thus interfering with each other by forming in the said blades a longitudinal corrugation 12 that is placed in the blade intermediate its 50 upper narrow end and its enlarged lower portion 13. These corrugations are depressed in the blades from their outer to their inner sides, thus forming the corrugation with its 55 concave portion 14 on the outer side of the blades. This formation enables the device to be readily cleaned, as will be understood, which would not be the case if the corrugation extended from the inner to the outer 60 side of the said blades.

Since the beaters revolve very rapidly owing to the relative large size of the drive wheel 1 and the number of cogs therein and the relatively small pinions 11, it is desirable 65 that splashing and spattering of the material

being operated upon outside of the receptacle 7 be prevented. As the beater blades revolve, the angular wall 15 of the corrugation 12 gathers the material, causing it to flow longitudinally therein and pass out their lower 70 ends 15', and thus prevent the material from slopping over the outside of the receptacle containing it, and also prevents small quantities of the material from being thrown from the cup, the same flowing longitudinally 75 through the corrugations instead of being splashed outside of the cup.

Therefore it will be observed that the corrugations strengthen the blades and prevent interference; that the manner of forming 80 these corrugations makes the device readily cleaned; that the corrugations and the long narrow tapered shape of the blades prevents the material from splashing or slopping outside of the receptacle; the whole structure 85 makes a machine that will be very satisfactory in its use.

From the above construction it will be observed that I produce an eight-blade beater, the blades of the beater shaped to form a 90 long narrow beater with its upper end narrower than its lower end; whereby an eight-blade beater is produced that will not pound or interfere in any manner in operation. It will also be observed that by constructing 95 the blades of the beaters specifically as herein described, they maintain their shape and prevent interference which would otherwise occur.

I have explained my present improvement 100 in specific detail yet I desire it understood that changes may be made therein without departing from the present improvement, so long as they come within a fair interpretation of the appended claims.

Having thus described my invention, what I desire to claim and secure by Letters Patent is:

1. A beater for the purpose described comprising two sets of beater blades each comprising four blades, each blade having a narrow bottom portion and extending in a straight line substantially from end to end and the two sets arranged side by side and the blades interlacing substantially throughout their length, and means for operating the said blades, substantially as described.

2. A beater for the purpose described comprising two sets of beater blades each set comprising four blades and all of the blades having narrow bottom portions and extending forward in a straight line substantially from end to end whereby the beater blades interlace substantially through their length and each blade provided with a longitudinal corrugation beginning substantially at the center of the blade and extending upward, the said blades interlacing substantially throughout their length, for the purpose set forth.

3. A beater for the purpose described com-

prising two sets of beater blades each set comprising four blades, the lower ends of the blades formed narrow and the blades extending upward in straight lines substantially from end to end, the blades interlacing substantially throughout their length and each blade provided with an inwardly extending

longitudinal corrugation beginning substantially at the center of the blade and extending upward, and means for rotating the said 10 blades, for the purpose set forth.

In testimony whereof I hereunto affix my signature.

LAVERN BORDWELL.
